UNITED STATES PATENT OFFICE.

JOHN R. WARREN, OF GRAND RAPIDS, MICHIGAN, ASSIGNOR TO JOHN R. WARREN, DONALD J. CAMPBELL, CHARLES E. JOHNSON, PAUL R. BEARDSLEY, AND CARL P. DAMM, TRUSTEES, ALL OF MUSKEGON, MICHIGAN.

ROTARY VALVE.

Application filed November 15, 1923. Serial No. 674,883.

To all whom it may concern:

Be it known that I, JOHN R. WARREN, a citizen of the United States, residing at Grand Rapids, in the county of Kent and 5 State of Michigan, have invented new and useful Improvements in Rotary Valves, of which the following is a specification.

The present invention relates to rotary valves; and its object is to provide a rotary 10 valve, for internal-combustion engines and the like, having improved means for preventing leakage.

This and any other objects hereinafter appearing are attained by, and the invention finds preferable embodiment in, the structure hereinafter particularly described in the body of this specification and illustrated by the accompanying drawings, in 15 which:

20 Figure 1 is a vertical central sectional view of a portion of an internal-combustion engine to which my invention is shown applied, certain parts being broken away;

25 Figure 2 is a diametrical sectional view of one of the rings employed in said structure;

Figure 3 is a side view of a second ring employed in said structure;

30 Figure 4 is a diametrical sectional view of the same; and

Figure 5 is an edgewise view of a portion thereof.

In the embodiment of my invention chosen for illustration by the drawings and for detailed description in the body of this specification, my invention is shown in connection with a four-cycle type of internal-combustion engine having six cylinders, 1, 2 and 35 3 thereof appearing in diametrical longitudinal section in Figure 1. The cylinders have pistons 4, 5, 6, furnished with connecting rods 7 for operating the cranks respectively on the crank shaft or engine shaft (not shown). At their upper ends, the cylinders have ports 61, 62, 63, respectively for

40 the admission of the operating fluid thereto and for the expulsion of the products of combustion therefrom. These cylinders are supported on the frame, designated generally 14, of the engine. The rotary valve 15, for controlling the admission of the operating fluid to the cylinders and for permitting the expulsion of the products of combustion therefrom, rotates in a bearing

or valve chamber in a valve-casing, designated generally 16, having ports communicating with the cylinders through the cylinders' said ports respectively, and being supported in connection with the frame 14.

In the construction shown, the casing 16 has a bushing 34 surrounding the valve non-rotatively and provided with openings 35 which register with the cylinders' ports respectively. The valve is hollow, having longitudinally-extending passages (not shown) 65 to which the fluid is supplied from a vent 26 in the frame, the fluid thence passing through a series of inlets 51 through the valve's wall and to each cylinder's port through openings 28 in the valve's wall, the 70 products of combustion being discharged from each cylinder through outlets 30 through the valve's wall and into its longitudinally-extending passage 32 opening at the end or ends of the valve through a 75 centrally-disposed outwardly-extending exhaust nozzle 9 communicating with the exhaust pipe 53.

The general construction of the illustrated 80 valve, its passages, inlets and outlets may correspond in general with Patent No. 1,278,533 issued September 10, 1918 on my application, such inlets and outlets through the valve's wall being so disposed angularly of the valve that the sequence of supply to 85 and exhaust from the several cylinders is properly timed. In such valves however, it is difficult to prevent leakage of the products of combustion from the exhaust nozzle of the valve into the valve casing or 90 bearing, inasmuch as this nozzle becomes very hot in operation, thus expanding and contracting greatly in its radial direction, so that a tight fit of leakage-preventing means surrounding the nozzle is difficult if 95 not impossible; and furthermore, the lubrication of the nozzle bearing in such surrounding means is likewise difficult or impossible.

The present invention has for its object 100 the prevention of such leakage adjacent the exhaust end of the rotary valve. To this end, I provide said exhaust nozzle 9 of the valve, and in addition thereto the following members: A ring 8 whose periphery 44 fits in the valve casing, preferably abuts fittingly against the end of the valve and surrounds said nozzle which turns freely in 105

5 said ring; a second ring 10 preferably fits between this ring 8 and the end 11 of the valve chamber or casing and fits around the nozzle 9, but may permit the nozzle's turning therein. The first ring 8 may be centrally recessed at 12 to receive the second ring 10, the circumferential rim 13 of the first ring 8 preferably abutting fittingly against the end 11 of the valve chamber or 10 casing as shown. The second ring 10 is shown "split," such split formation being preferably made by cutting the ring partially through radially as shown at 17 and then breaking it adjacent such cut as shown at 18. 15 It will be seen that by the provision of the exhaust nozzle 9, and the surrounding rings formed and fitting as described, leakage adjacent the exhaust end or ends of the rotary valve is very effectively pervented. Inasmuch as the ring 10 fits around the valve's 20 nozzle 9 (so as to prevent leakage between these parts), and inasmuch as said ring 10 abuttingly fits on the ring 8 (so as to prevent leakage between these rings), and inasmuch as the periphery 44 of the ring 8 fits 25 in the valve casing (to prevent leakage between ring 8 and the valve casing), it will be seen that products of combustion issuing from the mouth of the nozzle 9 cannot pass back beyond the ring 8 and enter the cylinders' ports, although the nozzle 9 extends loosely and non-fittingly through the ring 8 and although the ring 10 does not fit at its 30 outer periphery in the valve casing or in any part of the structure; and that, by reason of this non-fitting or spaced relation between the ring 8 and the valve's nozzle and between the ring 10 and the valve casing or other parts outside the ring 10, the nozzle 35 40 9 may expand and contract without causing leakage back into the valve casing and the cylinders' ports.

45 It being desirable that the ring 10 may fit as closely as possible around the valve's nozzle 9 but may nevertheless expand when necessary as this nozzle expands, said ring 10 is radially cut at 17 nearly therethrough and is then broken at 18 the rest of the way therethrough. If the cut 17 extended entirely through this ring, the part removed by such cutting would form a gap open through the ring; and if the ring were broken entirely through (no cut 17 being first made), this ring would remain tightly closed at the line of breaking unless and until the nozzle 9 expands enough to open the fissure, so that, until such fissure is thus opened, there would be no open passage through this ring 10; but, inasmuch as it is impracticable to break the ring 10 entirely through, the cut 17 is first made, whereupon the breaking at 18 of the ring is comparatively easy. It is thus manifest that the ring 10, formed as above described, provides a device (surrounding the valve's nozzle 9) which will expand with the valve's nozzle 9, and which will not be broken until the valve's nozzle 9 has expanded to a size which will not be encountered in normal use.

zle) which is as nearly leak-proof as may be in a packing ring of the character described, in view of the fact that the said nozzle must at times expand and thus more or less open the fissure formed by said breaking. The products of combustion have a certain lubricating quality which lubricates the bearings adjacent the nozzle 9. 70

In the illustrated construction, the rotary valve has a skew gear 43 between the third and fourth of the six cylinders, with which gear meshes a skew gear 42 on the shaft 40 driven by the engine shaft, for rotating the valve. 75

Without limiting myself to details of construction of the particular embodiment of my invention illustrated by the drawings or hereinbefore described, 80

I claim:

1. In an engine: a rotary-valve casing having an exhaust passage at its end; an engine valve rotatable in said casing and having an exhaust nozzle at its end adjacent said exhaust passage; a packing ring in which said nozzle freely turns, and fitting in the valve casing; a packing ring through which said nozzle fittingly extends and fitting the first-mentioned ring. 85 90

2. In an engine, a rotary-valve casing having an exhaust passage at its end; an engine valve rotatable in said casing and having an exhaust nozzle at its end adjacent said exhaust passage; a packing ring in which said nozzle freely turns, and fitting in the valve casing and having a centrally disposed recess in its side; a packing ring through which said nozzle fittingly extends and fitting the first-mentioned ring. 95 100

3. In an engine: a rotary-valve casing having an exhaust passage at its end; an engine valve rotatable in said casing and having an exhaust nozzle at its end adjacent said exhaust passage; a packing ring in which said nozzle freely turns, fitting in the valve casing and fitting between said end of the valve and said end of the valve casing and having a centrally disposed recess in its side; a packing ring through which said nozzle fittingly extends and fitting between the bottom of said recess and said end of the valve casing.

4. In an engine: a rotary-valve casing having an exhaust passage at its end; an engine valve rotatable in said casing and having an exhaust nozzle at its end adjacent said exhaust passage; a packing ring through which said nozzle extends, fitting in the valve-casing and abuttingly fitting said end of the valve; a packing ring through which said nozzle fittingly extends and fitting between the first mentioned ring and said end of the valve casing. 120 125

5. In an engine: a rotary-valve casing having an exhaust passage at its end; an engine valve rotatable in said casing and hav- 130

- ing an exhaust nozzle at its end adjacent said exhaust passage; a packing ring in which said nozzle freely turns, and fitting in the valve casing; a packing ring through 5 which said nozzle fittingly extends and fitting the first mentioned ring; at least one of said rings being cut partially through radially and then broken adjacent such cut to form a split ring.
- 10 6. In an engine: a rotary-valve casing having an exhaust passage at its end; an engine valve rotatable in said casing and hav-

ing an exhaust nozzle at its end adjacent said exhaust passage; a packing ring in which said nozzle freely turns, and fitting in 15 the valve casing; a packing ring through which said nozzle fittingly extends and fitting the first mentioned ring; at least one of said rings being split.

In testimony whereof I have hereunto set 20 my hand at Grand Rapids, Michigan, this 5th day of November, 1923.

JOHN R. WARREN.
